UNITED STATES PATENT OFFICE.

AMOS PIERCE AVERY, OF ST. PETERSBURG, FLORIDA.

COMBINATION GOLF-TEE BLOCK.

Application filed November 22, 1923. Serial No. 676,356.

To all whom it may concern:

Be it known that I, AMOS PIERCE AVERY, a citizen of the United States, residing in the city of St. Petersburg, county of Pinellas, and State of Florida, have invented a new and useful Combination Golf-Tee Block, of which the following is a specification.

My invention relates to improvements in 10 artificial golf tees, the object of the inventor being to provide:

(1) An artificial golf tee which will eliminate the making and placing of a natural tee.

(2) A combination of artificial golf tees 15 of different heights to accommodate golf players, both left and right handed, of varied ability.

(3) To provide a device of this character which will be simple, practical, economical 20 and durable both in construction and use.

I attain these objects by the mechanism illustrated in the accompanying drawings, in which—

Fig. 1 is a plan view of entire combination golf tee block;

Fig. 2, a side elevation;

Fig. 3, an end elevation;

Fig. 4, a vertical cross section through center line of one elevation showing detailed view of top surface.

Similar numerals refer to similar parts throughout the several views.

The golf tee block proper 1, from which arise the several elevations, or tees 2 which parts are a one and inseparable unit, all 35 composed of a firm but resilient substance, is fastened and secured to wood base 5 by means of screws and screw holes 4.

Each elevation or tee is provided with 40 a depression or slot 3, the purpose of such depressions being to provide a cup or resting place for golf ball.

In actual use golf tee proper 1 fastened to wood base 5 is set in earth in such manner as to permit only the elevations or tees 45 2 to protrude above the ground.

I am aware that prior to my invention artificial golf tees of the single tee variety have been made. I therefore do not claim 50 an individual artificial tee, but I claim:

A golf tee block having a plurality of tees of different heights provided with depressions forming ball seats, said tee block comprising an embedded block and resilient tee base fixedly secured to the upper surface thereof, said tees being integral with 55 said base.

AMOS PIERCE AVERY.
